UNITED STATES PATENT OFFICE.

CHARLES H. BUCHANAN, OF PHILADELPHIA, PENNSYLVANIA, ASSIGNOR
TO THE AMERICAN NOVELTY SHOE COMPANY, OF SAME PLACE.

DESIGN FOR A TRAVELING-BAG, &c.

SPECIFICATION forming part of Design No. 16,608, dated April 13, 1886

Application filed November 28, 1885. Serial No. 184,225. Term of patent 3½ years.

To all whom it may concern:

Be it known that I, CHARLES H. BUCHANAN, a citizen of the United States, residing at Philadelphia, in the county of Philadelphia and State of Pennsylvania, have invented a certain new and useful Design for Traveling Bags, Satchels, Cabas, &c.; and I do hereby declare the following to be a full, clear, and exact description of the invention, reference being had to the accompanying drawings, which form part of this specification, in which—

Figure 1 is an elevation of a bag showing my design, and Fig. 2 a sectional view of the same.

My new and original design for a traveling bag, satchel, or "caba" consists of a bag, satchel, or caba having its sides ornamented or decorated with strips or strands of braided or braid-like material arranged in parallel series, forming steps or overlaps at the edges, and imparting to the same a corrugated or ridged appearance.

In the accompanying drawings, illustrating a bag, satchel, or caba embracing my design,

A designates the side of the satchel or caba, composed of the parallel strips or strands BC, of braid-like or plaited appearance, said strands overlapping at their edges, so as to impart a corrugated or ridged effect to the surface, which renders the article ornamental and attractive.

Having described my design, what I claim, and desire to secure by Letters Patent, is—

The design herein shown and described, consisting of a bag, satchel, or caba having its sides ornamented or decorated with strips or strands of braided or braid-like material arranged in parallel series, forming steps or overlaps at the edges, and imparting to the surface of the bag, satchel, or caba a corrugated or ridged appearance.

In testimony that I claim the foregoing I have hereunto set my hand this 17th day of November, 1885.

CHAS. H. BUCHANAN.
